UNITED STATES PATENT OFFICE.

PETER K. HIGGINS, OF LOS ANGELES, CALIFORNIA, ASSIGNOR TO FREDERICK R. PARKER, OF CHICAGO, ILLINOIS.

ELECTRIC-LINE-APPARATUS PROTECTOR.

1,110,259.

Specification of Letters Patent.

Patented Sept. 8, 1914.

Application filed October 22, 1903, Serial No. 178,140. Renewed July 22, 1913. Serial No. 780,571.

To all whom it may concern:

Be it known that I, PETER K. HIGGINS, a citizen of the United States of America, residing at Los Angeles, in the county of Los Angeles and State of California, have invented a new and useful Electric-Line-Apparatus Protector, of which the following is a specification, reference being had to the accompanying drawings, illustrating same.

My invention relates to means for protecting telephone or other electrical apparatus and circuits from damage resulting from lightning or from the accidental contact of the telephone or other line with a line carrying an electric current which would be injurious to the telephone or other line or to the apparatus connected therewith, or to the users of such apparatus, and sometimes to all of these; and the principal object thereof is to provide a simple and efficient device for that purpose. Other objects will be apparent from the following specification. I accomplish this purpose by the protector described herein, the preferred form of which is illustrated in the accompanying drawings in which:

Figure 1 is an end elevation of the protector, and Fig. 2 is a longitudinal cross-sectional view of the protector, taken on line 2-2 of Fig. 1.

Like characters refer to like parts in the several figures.

In the drawings A is the insulating base of my protector to which are secured the metallic springs B, the upper ends of which are adapted to stand normally in the position shown in dotted lines in Fig. 2. To the base of these springs are secured the line wires C and D. These springs support the body of the protector. The metallic end pieces E have grooves E' therein for the reception of the side wings B' of the springs, the central sections B'' of the upper portions of the springs passing on the outside of the metallic ends as shown. These metallic end pieces are preferably provided with studs E'' which project into sockets F' in the graphite core F and are held in such sockets by solder G which is fused around the studs and then allowed to cool. This solder thus unites the metallic end pieces to the graphite core. It may have a low melting point. This core is preferably a round

rod and may be termed the thermal rod. It 55 is surrounded by a dielectric of celluloid, or other suitable material, which provides a suitable air space spark gap between the said core and the tube H of conducting material, preferably of carbon, which surrounds the 60 said core. The celluloid dielectric will not burn upon the passage of an electric spark through the said air-space or spark-gap, while inclosed by the thermal rod and tube H, because the air is kept therefrom. 65 When, however, a continued arc is formed in the said air-space or spark-gap, the celluloid dielectric will become softened from the heat of the arc and will then permit the spring J to press the tube H into contact 70 with the thermal rod, thus stopping the arc and the consequent heating. The dielectric is preferably perforated as shown in Fig. 2, so as to break up or scatter a heavy discharge. It will be readily seen that the tube 75 H is of noninflammable material, and that it protects the inflammable dielectric from burning under various conditions. The tube H of carbon is insulated from the metallic ends by washers I of any suitable insulating material, preferably mica. Secured to the base is the contact spring J the free end of which engages the carbon tube when the body of the protector is in place in the springs. This contact spring is connected by 80 wire K with ground L or other suitable capacity. Secured to the base and normally out of electrical contact with the wire C is contact M which is connected by wires N and K to ground L or other suitable capacity. 85 After the body of the protector is formed as before stated the free ends E of the springs B are pressed toward each other and the grooved ends are slipped over the wings B', thereby holding the body of the protector 90 securely in place and completing the circuit through the line wires. This protector is 95 preferably designed to be placed at the terminals of the cables at the central office of a telephone system and also at the telephone 100 instruments of the subscribers.

Now should the telephone line accidentally be engaged by another line carrying a current of considerable volume but of low voltage, the resistance encountered in the 105 graphite core by an abnormal current traversing same would generate sufficient heat to melt the solder which holds the metallic

ends thereto, whereupon the springs would cause the metallic ends E to separate from the body of the protector and thereby permit the spring B on the left of Fig. 2 to engage the contact M which is grounded, thereby switching the injurious current to ground and preventing it from injuriously affecting the instrument of the subscriber or the apparatus at the central station connected therewith.

Should the telephone line accidentally be engaged by another line carrying a current of high voltage, this current would arc through the dielectric and pass to ground through the contact spring J and wire K. Lightning would pass to ground in the same manner. However, if the arc continues sufficiently to soften the dielectric, the spring J will then press the conductor H into contact with the thermal rod or core of the protector and thus stop the arc and at the same time carry the injurious current off to ground.

By this construction a simple and efficient protector is provided for a telephone or other system in which currents of low tension are used.

I do not wish to limit this invention to all of the exact details herein set forth, as many modifications may be made therein without departing from the scope of the appended claims. I also wish it to be understood that I may use the various features of this invention collectively or separately from each other, as, for instance, the features of the high-potential electricity arrester without the features of the sneak-current protector of electrothermal device, and the feature of the non-inflammable casing for the protector without the features of the high-potential electricity arrester.

The sneak-current protector or heat-cartridge herein set forth forms the subject matter of a divisional application of the present application; which divisional application was filed on December 15, 1913, under Serial No. 806,826.

Having thus described my invention what I claim as new and desire to secure by Letters Patent is:—

1. In a protector for electric circuits, having a thermal core containing fusible material therein; an envelop of carbon surrounding said thermal core and separated therefrom by a dielectric.

2. The combination with an electrothermal protector having a thermal core and separate thermally-releasable retaining means under control thereof, of an envelop of conducting material surrounding the said core and separated from the body thereof by a thin dielectric member to provide a high-potential electricity arrester.

3. The combination with an electrothermal protector having a resistance heater and

separate thermally-releasable retaining means under control thereof, of a conductor surrounding the heater and closely associated with the body thereof to provide a high-potential electricity arrester.

4. A high-potential electricity arrester having a dielectric member of celluloid provided with many small perforations therethrough to scatter the discharge through the arrester.

5. In a high-potential electricity arrester having electrodes of solid material, a dielectric member of heat-susceptible material with provisions for permitting the discharge of electricity through air, interposed between the said electrodes whereby the latter are permitted to come together upon the softening of the dielectric member.

6. A high-potential electricity arrester having a dielectric of heat-softenable insulating material between the electrodes, provided with many small openings therethrough to scatter the discharge through the arrester.

7. In a high-potential electricity arrester having electrodes of solid material, a dielectric member of celluloid interposed between the electrodes and having provisions for permitting the discharge of electricity through air, the said dielectric when softened by excessive heating permitting the electrodes to come together to form a conductive path through the arrester.

8. In a high-potential electricity arrester having electrodes, a heat-softenable dielectric interposed between the electrodes and having provisions for permitting the discharge of electricity thereacross through air, the said dielectric when softened by excessive heating permitting the electrodes to make conductive connection with each other to form a conductive path through the arrester.

9. In a high-potential electricity arrester having electrodes of solid material, a heat-softenable dielectric between the electrodes, the said dielectric when softened by excessive heating permitting the electrodes to make conductive connection with each other to form a conductive path through the arrester.

10. A high-potential electricity arrester having electrodes and a heat-softenable dielectric between the electrodes adapted and arranged to be softened by excessive heating in the arrester whereby the electrodes are permitted to make conductive connection with each other.

11. A dielectric for a high-potential electricity arrester, comprising heat-softenable insulating material provided with many small openings therethrough to scatter the discharge through the arrester.

12. A dielectric member for a high-potential electricity arrester, comprising a piece

of celluloid having provisions for permitting the discharge of electricity thereacross through air.

13. A dielectric for a high-potential electricity arrester, comprising heat-softenable insulating material having provisions for permitting the discharge of electricity thereacross through air.

In witness that I claim the foregoing I have hereunto subscribed my name this 15th 10 day of October, 1903.

PETER K. HIGGINS.

Corrections in Letters Patent No. 1,110,259

It is hereby certified that in Letters Patent No. 1,110,259, granted September 8, 1914, upon the application of Peter K. Higgins, of Los Angeles, California, for an improvement in "Electric-Line-Apparatus Protectors," errors appear in the printed specification requiring correction as follows: Page 1, line 58, after the words "air space" insert the word *or*; same page, line 92, after the word "ends" strike out the reference letter "E"; same page, line 94, after the word "ends" insert the reference letter *E*; page 2, line 2, after the word "cause" insert the words *at least one of*; same page, line 38, for the word "of" read *or*; and that the said Letters Patent should be read with these corrections therein that the same may conform to the record of the case in the Patent Office.

Signed and sealed this 10th day of November, A. D., 1914.

[SEAL.]

R. F. WHITEHEAD,

Acting Commissioner of Patents.
